United States Patent Office.

C. H. RUDD AND GEORGE W. SHAWK, OF CLEVELAND, OHIO.

Letters Patent No. 68,577, dated September 3, 1867.

IMPROVEMENT IN ELECTRO-MAGNETIC PUMPS.

The Schedule referred to in these Letters Patent and making part of the same.

TO ALL WHOM IT MAY CONCERN:

Be it known that we, C. H. RUDD and GEORGE W. SHAWK, of Cleveland, in the county of Cuyahoga, and State of Ohio, have invented certain new and useful Improvements in Electro-Magnetic Pumps; and we do hereby declare that the following is a full and complete description of the construction and operation of the same, reference being had to the accompanying drawings, making a part of this specification, in which—

Figure 1 is a side view of the machine.

Figure 2 is a top view.

Figure 3 is an end view.

Figure 4 is a transverse section.

Like letters of reference refer to like parts in the views.

In fig. 2, A A' are a pair of helices, which are constructed in the ordinary way, with insulated coiled wire upon spools B, and central or core magnets C, all of which are properly insulated and connected to the battery by the usual negative and positive poles and conductors. A pair of these helices is placed at each end of the table D, as shown in fig. 2, between which is arranged a pump, constructed in the following manner: D' is a cylinder, secured to the table by a band, E. To this cylinder is fitted a piston, F, fig. 4, which may be constructed in the same manner as the piston of an ordinary steam engine, with a head and follower, and elastic ring packing G, all of which are placed upon the rod H, and secured to the same by a nut, I. It will be seen that the piston-rod H passes through the head, and projected from each side of the same through the ends of the cylinder, guided and sustained by the sleeves or stuffing-boxes I', as shown in fig. 2. Each extreme end of the rod is furnished with a bar, J J', to which reference will hereafter be made. In the chamber K is located a button-valve, K', which is made to open inward. A valve corresponding to this is arranged and located on the opposite end of the cylinder; and relatively in the same position, above this valve, and in the same line of diameter, is another chamber and valve, L L', of the same size and construction, which, however, unlike the other, open outward. A valve corresponding to this is also arranged on the opposite end of the cylinder, and relatively occupying the same position. Thus each end of the cylinder is alike provided with two valves, the lower one of which opens inward and is the inductive valve, and the upper one opening outward, the eduction, and which are connected by pipes to the well or water.

Having thus described the construction and general arrangement of the machine, the practical operation of the same is as follows:

The helices on being connected to the battery by the usual positive and negative wires M M' and N, secured in the cups N', the magnet C in the helices A' is charged and attracts the armature J to itself, thus drawing the piston F in that direction more or less, as the distance that the armature may be attracted. As the piston moves to the right, the water is forced from the cylinder through the valve L'. At the same time the valve K opens on the opposite end of the cylinder, and through which the water flows into the cylinder and fills the space between the head and piston. On breaking the circuit established in the helices A', and charging the helices A, the armature J' is attracted by the magnets C', which draws the piston-ball to the opposite end of the cylinder, forcing the water out through the upper valve L'. At the same time the lower valve K' is opened by the external pressure of the water, which flows into the cylinder and fills the space between the piston and head, as in the former case, and so on alternately. As the connection is made and broken in each pair of helices, the pump is made to work reciprocally, receiving and discharging water from each end of the cylinder.

The electro-magnet has long been looked to as an agent through which electricity could be used as a motive power. The machines that have been constructed, having in view this end, have failed mainly from the fact that the power obtained and exerted diminishes so rapidly as the distances between the magnet and the object to be attracted increases, the power diminishing as the square of the distance increases. It becomes, therefore, necessary to find some means of using the magnet so that the distance between it and the armature, or the object to be attracted, shall be so short as to secure the greatest possible attractive force. With the pump above described, strokes of the piston a sixteenth of an inch or less may be made available, as the diameter of

the cylinder may be increased, and thus compensates with a large diameter and a rapid stroke what it may lack in length, and thereby obtain the desired result, viz, pumping air or water in the manner as above described.

We do not confine ourselves to any special way of changing current from one to the other of magnets A A', in order to produce a reciprocating motion of pump, but would suggest the following as one means: Let rod *a*, fig. 2, be one side of a small battery, and adjusting-screw *b*, fig. 2, be the other side. The motion of armature *J* towards its magnet A' would bring these two sides together, producing a current. We propose to pass this current through a small magnet, which we propose to use in connection with the pump. The charging of this auxiliary magnet by the small battery referred to, is designed to depress one end of a balance-lever, which depression closes the circuit of the large battery through magnet A. This lever must be provided with an attachment by which it will remain depressed until the magnet A has done its work, viz, has drawn armature *J'* as near to itself as is possible without touching, at which moment rod *c* must strike adjusting-screw *d*, which will close a circuit from the small battery through another small magnet, depressing a lever that will close the circuit through magnet A', and at the same moment draw the armature of the first small magnet away from said magnet for another stroke of the piston. Thus both sides are operated, and operate substantially and alternately alike, thereby producing a reciprocating movement of the piston. We have set our cups in the drawing to agree with our suggestions, those connected to the armatures *J* and *J'* by spiral wires being one side of small battery, and brass strips *b'* holding adjusting screws *b d*. The other cup *N'* is the point for attaching one pole of the large battery, from which cup a wire, *n*, runs to one side of each large magnet A A'. Cups *n''* are to be so connected to our auxiliary instrument that the opposite side of the large battery may be thrown to either one as is necessary to produce the movement of the piston.

What we claim as our improvement, and desire to secure by Letters Patent, is—

1. The magnets A A', as arranged, in combination with the armature J J', piston F, and rods *a c*, in the manner and for the purpose substantially as set forth.
2. The application of the electro-magnetic apparatus to the pump, when constructed and arranged to operate conjointly as and for the purpose substantially as specified.

C. H. RUDD,
GEO. W. SHAWK.
